MACHINE EMPLOYING WORK ROLLS WITH
BRAKE CONTROLS

Peter A. Brill, Marblehead, and George E. McLaughlin, Brookline, Mass., assignors to The Turner Tanning Machinery Company, Portland, Maine, a corporation of Maine

Application January 29, 1953, Serial No. 333,971

11 Claims. (Cl. 69—42)

1

This invention relates to machines for treating sheet materials, such as hides and skins, and more particularly, to machines employing work rolls which must be closed upon the work with such control of closure that the workpiece is not marked or gouged thereby. This invention is disclosed as being embodied in a shaving machine of the type shown in United States Letters Patent No. 1,996,877, granted April 9, 1935 in the name of Paul Niessen. It is to be understood, however, that this invention is not, in its broader aspects, limited to a shaving machine or to the particular work roll actuating system herein disclosed.

In the type of machines wherein the work rolls must be brought into their operative positions with a workpiece inserted therein, it is of extreme importance that the action of closure be gentle in nature so that the workpiece is not marked or gouged. In such machines the range of opening or closing movement of the rolls, with respect to each other, is often relatively small, particularly in a shaving machine wherein such range is approximately seven-eighths of an inch. Recently improved means have been provided for opening and closing such rolls through the use of fluid motors. This has increased the above-mentioned problems of marking or gouging workpieces in machines of this type.

Various expedients have been used to avoid the shock of closure and consequent marring of the workpiece. For example, the United States Letters Patent No. 2,418,913, granted April 15, 1947 to F. S. Stout et al., a cushioning cylinder is shown for reducing the shock of closure in an ironing machine. Likewise in United States Letters Patent No. 2,586,879, granted February 26, 1952 in the name of R. J. Stehling, hydraulic means are shown for applying pressure to the fixed roll in a fleshing machine. These methods of reducing the shock of bringing the workpiece carrying roll into a gentle engagement with some type of work roll are not only difficult and complex properly to adjust but, more important, they tend unduly to slow down the rate of motion so that time is lost during the closing of the rolls and a production loss results therefrom.

It is an object of this invention to provide improved means for quickly bringing a work carrying roll into and out of operative engagement with a work roll in such a manner that there is no gouging of the workpiece.

It is an object of this invention to provide braking means which are gradually increased as a work carrying roll is brought into operative rela-

2

tion to a work roll and, to do so, in such a manner that little or no braking effect is applied during the acceleration of the work carrying roll. The braking means, however, apply an increasing braking force so as completely to overcome the inertia forces present as the work carrying roll is decelerated as it comes into its operative position. More particularly the features of this invention are shown in a shaving machine of the type disclosed in the aforementioned Niessen patent in which a sub-frame is pivotally mounted on side portions of a main frame and carries a work carrying roll or bed roll. This sub-frame is pivoted into and out of operative engagement with a work roll or shaving roll by means of a fluid controlled linkage system. Normally in operation the bed roll is in operative relation with the shaving roll and work is introduced therein. When it is desired to withdraw work from the machine, the operator trips the treadle which actuates the fluid motor and linkage system to bring the bed roll out of operative engagement. The work is then turned end for end, the treadle is tripped and the bed roll is brought into operative position with the shaving blade and the workpiece is then reinserted to process the remainder of the workpiece. Under this situation it is of little consequence if the bed roll is brought into operative engagement with the shaving roll with a great amount of shock. However, during an operation on the skin often times due to the nature of the workpiece it is desired momentarily to release the bed roll from its operative position so that said workpiece may be properly readjusted and then to close the bed roll into its operative position while the workpiece is still inserted therein.

In such cases where the bed roll must be brought into operative engagement while the workpiece is in the machine, the closing action at the last instant of closure must be very gentle in order to avoid any marking or gouging of the leather surface. For this purpose, and in accordance with a feature of this invention, a brake drum is provided within the fluid controlled linkage system which pivots the sub-frame to bring the bed roll into operative position. Also within said linkage system is a brake band, one end of which is attached to a link within said system, and the other end of which is yieldingly connected to the main frame of the machine. The arrangement of the brake band and brake drum is such that during the acceleration of the sub-frame to pivot it by means of the linkage system into operative relationship, little or no

braking force is applied to said linkage system. This arrangement allows the full power of the fluid motor to be available for overcoming the high inertia forces inherent in accelerating the pivoted sub-frame which is of a considerable mass. As the motion of the linkages continues, the braking power is progressively increased due to the arrangement connecting the brake band yieldingly to the main frame so that the large mass of the sub-frame is decelerated by the brake arrangement which absorbs and overcomes the high inertia forces of deceleration in bringing the bed roll to a stop in its operative position.

The above-described arrangement is of particular advantage in machines of this type where the extent of movement is limited and yet must be made rapidly but without allowing the members in motion to come to a stop under shock conditions.

These and other important features of the invention will now be described in detail in the specification and pointed out in the appended claims.

In the drawings,

Fig. 1 is a section through a shaving machine embodying features of the present invention;

Fig. 2 is a section taken along the line II—II of Fig. 1 but with certain parts omitted for the sake of clarity;

Fig. 3 is an enlarged view of some details of the machine taken along the line III—III of Fig. 2; and

Fig. 4 is a diagrammatic representation of the fluid pressure system for operating the mechanism shown in Figs. 1 and 2.

The machine herein disclosed and in which the present invention is embodied comprises a main frame 10 (Fig. 1) and a pivoted sub-frame 12. The main frame 10 is of the usual configuration adopted in shaving machines as is fully described in the aforementioned Niessen patent and is generally U-shaped as viewed from the side. At the front of the machine a heavy horizontal member 14 is utilized to join the two side portions of the frame 10 together rigidly. Both ends of a horizontal shaft 16 are rigidly held in the frame 10 and upon the shaft 16 is pivoted the sub-frame 12, above mentioned. The latter is in the form of the letter Y having two upstanding arms although they do not appear separately in the drawings. Integral with sub-frame 12 is a depending leg 20 into which is threaded an adjusting screw 22 which in turn is axially and rotatably mounted on a rod 32. The rod 32 is integral with a T-shaped member 26 that is secured to a shaft 28 by a set screw 30. The left-hand end of the screw 22 abuts the T-shaped member 26 (Fig. 1) while a hand wheel 24 is secured to its other end. A second hand wheel 34 is threaded on the right-hand end of the shaft 32 so that its hub may engage the adjusting screw 22 and lock it in a predetermined position.

The ends of the shaft 28 are pivotally connected to the ends of two links 36 and 40. The other ends of the links 36 and 40 are pivoted on pins 42 and 44 which are held in non-rotatable relation, by means of set screws 46 and 48, to two curved arms 50 and 52. These two curved arms are integral with an elongated sleeve member 56 (Fig. 2) which is freely journaled on a non-rotatable shaft 58 the ends of the latter being supported by the side portions of the frame 10. Fig. 2 shows how one end of the shaft 58 is held to a side portion of the frame 10 by means of a set screw 60. Lengthwise movement of the

sleeve 56 is prevented in one direction by a collar 62 which is secured to the shaft 58 by a set screw 64 and in the other direction by a brake drum 70 secured to the shaft 58 by a headed key (not shown).

At the end of the sleeve member 56 abutting the collar 62 is provided an arm 74 which is extremely heavy and rugged in construction. This arm is recessed along its length to receive an elongated member 76 which is attached to the arm 74. The outer end of the member 76 is pivotally connected by means of a pin 78 to a clevis 80 formed on the lower end of a piston rod 82 (Fig. 1) which is part of a fluid motor 84. The cylinder of the motor 84 is pinned at 86 (Fig. 1) to a bracket 88 joined to the inner surface of a side portion of the frame 10.

The brake drum 70 is, as indicated above, fixed to the shaft 58 and is non-rotatable. Surrounding the brake drum is a brake band 73 (Fig. 3) to which is attached a customary brake lining 75. The band and lining are held in proper axial position with respect to the brake drum 70 by means of two clips 77 and 89.

Integral with the elongated sleeve member 56 is a protuberance 79 (Fig. 3) to which is secured a pin 81. One end of the brake band 73 is looped about the pin 81 and doubled back and attached to itself. The other end of the brake band 73 bears a small bracket 83 in which a hole is formed to receive the reduced end 85 of a threaded shaft 87. The other end of the shaft 87 is slidably mounted in an L-shaped block 90 one leg of which is secured to a stiffener rod 92 (Fig. 2). The rod 92 is an integral part of the machine frame 10, one end being attached to the frame reinforcing horizontal member 14 and the other end being attached to a part of the frame 10 which is not shown in the drawings.

A stop nut 94 is pinned to the rod 87 and abuts the bracket 83. Threaded upon the rod 87 are two lock nuts 96 and 98 which serve by means of a washer 100 to confine a coil spring 102 against one end of the block 90.

The upper end of the sub-frame 12 (Fig. 1) is provided with a shelf 106, a work guiding roll 108, and a bed roll 110. The bed roll 110 is arranged to be moved into open or closed working relation with a bladed roll 112 which is journaled in the machine frame 10 and driven by power means, not shown in the drawing.

A wiper or flipper unit 114 is also journaled in the machine frame 10 in a suitable position and driven in the direction indicated to prevent wrapping of work about the bladed roll 112.

A foot treadle 116 is mounted at the front of the machine and is arranged to operate a pilot valve 118 which in turn is arranged to operate a control valve 120. Fig. 4 diagrammatically illustrates the alternative directions of fluid flow through suitable connections to the fluid motor 84. The lighter lines indicate fluid flow when the treadle 116 is tripped to bring the bed roll into its operative position and the darker lines indicate fluid flow when the treadle 116 is tripped to bring said roll out of its operative position.

In operation, the shaving roll 112 and the flipper unit 114 are constantly rotating in the directions indicated in Fig. 1. The foot treadle 116 is depressed to operate the pilot valve 118 and the control valve 120 so that the fluid flow of this conventional arrangement causes the piston rod 82 of the fluid motor 84 to move in a downward direction so as to come to rest in the position shown in Fig. 1. During the downward move-

ment of the piston rod 82 the elongated sleeve member 56 turns clockwise as viewed in Figs. 1 and 3. When this motion is first initiated, there is little or no braking power applied by the brake band 73 to retard movement of the sleeve 56 in relation to the fixed brake drum 70 thus allowing the full force of the fluid motor 84 to be available in accelerating the heavy mass of the sub-frame 12 through the elongated sleeve 56 and the links 36, 40, the T-shaped member 26 and the adjusting screw 22. However, as this clockwise motion of the sleeve 56 continues, the brake band 73 is drawn likewise in a clockwise direction by the pin 81 attached to the sleeve 56 in such a manner that the spring 102 is compressed so as rapidly to build up a braking force and at the time when the bed roll 112 has reached its operative position the braking force is substantially equal to the inertia forces arising from decelerating the sub-frame 12 and the fluid motor 84. The operative position of the sub-frame 12 is determined by the right-hand end of the rod 32 abutting the horizontal member 14 in conjunction with the adjusted position of the sub-frame 12 on the adjusting screw 22. A workpiece W is then inserted into the machine and is carried to the position shown in Fig. 1. After a portion of the work has been completed, usually more than half of the workpiece, the machine is again cycled by tripping the treadle 116 so that the fluid motor 84 is operated by the flow of fluid as indicated by the heavy lines in Fig. 4 to raise the piston rod 82 and cause the sleeve 56 to rotate in a counterclockwise direction as viewed in Fig. 1. A lug 130 attached to a side portion of the main frame 10 is provided and disposed in the path of travel of the arm 74 to limit the extent of motion of the sleeve 56 and thereby limiting the extent of opening of the bed roll 110 through the linkage system previously explained. The brake band 73 has no tendency to retard the counterclockwise motion of the sleeve 56 since the forces and braking effect are so arranged as progressively to resist rotational motion only in a clockwise direction. In this manner the time required for opening the rolls is dependent only upon force available from the fluid motor 84 and is not affected by the braking arrangement previously described.

It will be appreciated that the braking arrangement above described operates effectively to absorb the forces of closure progressively in such a manner that the bed roll 110 may be expeditiously brought into operative relationship with the shaving roll 112 in such a manner that no shock occurs and in the last instant of closure the action is quite gentle. As pointed out above, this is of extreme importance when it is desired to release the bed roll from its operative position to readjust a workpiece W without removing it entirely from the machine and then to bring said bed roll into operative position with the workpiece upon it. It will also be appreciated that the particular arrangement herein described is such that the means used to absorb the shock of closure have no tendencies to cause the bed roll 110 to move or yield out of its operative relation with the shaving roll 112.

Having thus described our invention, what we claim as new and desire to secure by Letters Patent of the United States is:

1. A machine for treating sheet materials including a bladed roll journaled on a main frame, a sub-frame pivoted as a unit with respect to said main frame, a bed roll journaled in said sub-

frame and arranged parallel to said bladed roll, a brake drum mounted rigidly on and with respect to said main frame, means for pivoting said sub-frame to bring the bed roll into cooperative or closed relation to said bladed roll, and a brake band on said brake drum having one end connected to said main frame and the other end to said sub-frame to move with the latter for tightening the brake band.

2. A machine for treating sheet materials including a bladed roll journaled on a main frame, a sub-frame pivoted to said main frame with one end supporting a bed roll parallel to said bladed roll, means for pivoting said sub-frame to bring the bed roll into cooperative relation to said bladed roll, and a brake mounted for effective action between said main frame and said sub-frame.

3. A machine for treating sheet materials including a bladed roll journaled on a main frame, a sub-frame pivoted as a unit with respect to said main frame, stop means determining the extent of motion of said sub-frame, a bed roll carried by said sub-frame and arranged parallel to said bladed roll, a brake drum mounted rigidly with respect to said main frame, means for pivoting said sub-frame to bring the bed roll into cooperative relation with said bladed roll, and a brake band on said brake drum having one end resiliently connected to said main frame and the other end pivotally connected to said sub-frame for movement therewith.

4. A machine for treating sheet materials including a bladed roll journaled on a main frame, a sub-frame pivoted as a unit with respect to said main frame, a bed roll carried by said sub-frame and arranged parallel to said bladed roll, a brake drum fixedly mounted with respect to said main frame, fluid pressure operated means for pivoting said sub-frame to bring the bed roll into and away from cooperative relation with said bladed roll, and a brake band on said brake drum with one end connected to said main frame and the other end being attached to said sub-frame to move therewith.

5. A machine for treating sheet materials such as hides, skins and leather including two work rolls in parallel relation, a main frame in which one of said rolls is journaled, a sub-frame in which the second of said rolls is journaled, said sub-frame being arranged to pivot with respect to said main frame permitting opening and closing movements of said rolls, and a brake mounted for effective action between said main frame and said sub-frame to resist the shock of roll closure.

6. A machine for treating sheet materials including a work roll journaled on a main frame, a sub-frame pivoted as a unit with respect to said main frame, a second work roll journaled in the said sub-frame and arranged parallel to said first work roll, a shaft mounted horizontally in the base of said frame, a brake drum attached to said horizontal shaft in non-rotatable relation to said frame, and fluid pressure operative means for pivoting said sub-frame to bring the second work roll into and away from cooperative relation with said first work roll, said fluid pressure operative means comprising a fluid pressure motor, a pilot valve for controlling the said motor and a treadle for controlling the said pilot valve.

7. A machine for treating sheet materials including a main frame, a first work roll journaled in said main frame, a sub-frame pivoted to said main frame, a second work roll journaled in said sub-frame for opening and closing movement in

cooperation with said first work roll, and a brake connected for effective action between the said two frames to resist the said closing movement of the said second work roll.

8. A machine for treating sheet materials including two frames, a work roll journaled in each of said frames, said frames being relatively movable to bring the work rolls into closed relation, means for effecting such relative movement, and a brake non-yieldingly connected by means of pivoted members to one of said frames to absorb the shock of roll closure.

9. In a machine for treating sheet materials having a work roll journaled on a main frame, a second work roll and means for bringing the second work roll into operative relation to said first work roll, a fixed brake drum, a brake band encircling said drum, and resilient means acting against a fixed member for holding one end of said band in its encircling relationship, the other end of said band being secured to said work roll moving means in such manner that as the second roll is brought into its operative position a braking force is progressively applied to said motivating means thereby to absorb the shock of closure.

10. In a machine for treating sheet materials having a work roll journaled on a main frame, a second work roll and means for bringing the second work roll into operative relation to said first work roll, a fixed brake drum, a brake band en-

circling said drum; and a spring acting between a fixed member and one end of said brake band for retaining said brake band in its encircling relationship, the other end of said band being secured to the work roll motivating means in such manner that as the second roll is brought into its operative position a braking force is progressively increased to eliminate the shock of closure.

11. In a machine for treating sheet materials having a work roll, a second work roll, means for bringing said second work roll into operative relation to said first work roll comprising a fluid motor and a foot treadle for operating said motor, an elongated sleeve pivotally mounted on a fixed shaft and connected to said fluid motor, a brake drum affixed to said shaft, a brake band encircling said drum, one end of which is fixed to a protuberance from said sleeve, and the other end of which is yieldingly held in its encircling position by a spring abutting a fixed member attached to said main frame, and links connecting said sleeve to a sub-frame in which the second roll is rotatably mounted, whereby when the foot treadle is depressed a braking force is progressively applied to said sleeve to reduce the consequent shock of bringing said second work roll into its operative position.
